UNITED STATES PATENT OFFICE.

SAMUEL GOLDSTEIN, OF NEW YORK, N. Y.

FUR CLASP.

Application filed February 11, 1922. Serial No. 535,677.

To all whom it may concern:

Be it known that I, SAMUEL GOLDSTEIN, a citizen of the United States, and resident of New York city, in the county of New York and State of New York, have invented certain new and useful Improvements in Fur Clasps, of which the following is a specification.

This invention relates to a clasp and more particularly to a fur clasp; and has special reference to the provision of a novel and improved clasp adapted for attachment or attached to the animal head of a fur piece such as fur neck-piece or scarf.

As is well known, for fastening or securing the head piece of a fur scarf to the tail or body portion thereof when the scarf is worn about the neck of the user, the head piece is provided with a clasp adapted for engaging or clasping the body portion or tail piece of the fur scarf or garment. The clasps previously employed for this purpose usually comprise upper and lower pivoted jaw members, the upper jaw member being attached to and usually received within and concealed by the animal head of the fur piece, with the lower jaw member movable relatively thereto and arranged for occupying the position of the lower jaw of the animal head. In prior constructions of clasps of this type, the jaw members have usually been made of sheet metal, the said jaw members being provided with overlying metal flange portions providing the bearings for the hinge pintle or pivot pin of the clasp.

The lower metal jaw member which is arranged external to and is movable relatively to the head piece of the fur is usually provided with a cover or sack of knitted fabric such as silk, this to the end of concealing from view the metal construction of the clasp and to the end of providing some means harmonizing with the characteristics and appearance of the fur head. The clasps made in this manner, however, do not effectually serve the purposes for which they are intended, numerous disadvantages and defects from the viewpoints of use and appearance being inherently present in these clasp constructions provided. In use, for example, the knitted sack or cover has a relatively short life and after some fingering by the user becomes worn and torn, presenting a ragged and uncouth appearance, and after further wear exposing undesirable metal portions of the clasp to view. Fur-

thermore, the metal flanges forming the hinge pintle receiving elements, in opening and closing of the jaw members, have been found to have a shearing action, the hair of the fur clasped between the jaws being oftentimes caught and pulled or sheared during clasping and unclasping action. In appearance the lower fabric covered jaw member does not present sufficient "body" and does not present the appearance for simulating the lower jaw of the animal or for harmonizing with the character of the fur head used. Moreover, the fabric sack or cover is incapable of concealing from view the metal portions of the pintle-bearing flanges, it being necessary in practice to sew or stitch the garment head with great care where exposure of such metal portions is desired to be avoided. To eliminate these disadvantages and defects in the appearance and use of fur clasps of prior construction and to provide a fur clasp which combines the qualities and characteristics of durability, efficient serviceability, effective simulation of the appropriate part of the animal head, neat appearance and attractiveness is a prime desideratum of my present invention.

The principal objects of my present invention may be said to include, besides the provision of a clasp having the characteristics above enumerated, the further provision of a clasp in which the lower jaw member is made of a molded material such as composition material and shaped to provide the "body" and appearance of the lower jaw of the animal head; the provision of a clasp of this nature in which the upper jaw is pivotally connected to the lower jaw in a manner to effectually minimize or prevent the undesirable "catching" and shearing of fur during clamping use of the clasp; the still further provision of a clasp of the nature referred to in which the lower jaw member is shaped to provide pintle-bearing portions so correlated with the corresponding portions of the upper jaw as to effectively conceal from view all metal portions and the still further provision of a clasp of this nature which is simple in construction, effective in operation and which may be manufactured and sold at low cost.

To the accomplishment of the foregoing and such other objects as may hereinafter appear, my invention consists in the elements and their relation one to the other as hereinafter particularly described and

sought to be defined in the claims, reference being had to the accompanying drawings which show a preferred embodiment of my invention, and in which:

5 Figure 1 shows a perspective view of the animal head of a fur piece with my clasp attached thereto and forming part thereof,

10 Figure 2 is an elevational view of the same with parts shown in cross section and other parts broken away,

15 Figure 3 is a perspective view of the clasp detached, and

20 Figure 4 is a view taken in cross section on the line 4—4, Figure 2.

25 Referring to the drawings, the clasp of my invention is constructed for attachment to the animal head of a fur piece, this being particularly shown in Figures 1 and 2 of the drawings, wherein the clasp C of my invention is shown associated with and attached to the head H of a fur piece such, for example, as a neck-piece or scarf. The clasp C comprises the relatively movable upper and lower jaw members j' and j² pivoted one on the other, the upper jaw member j' being attached to the animal head H as by being received within the mouth of the head and completely housed by and concealed within the same, the said upper jaw j' being 30 inserted within the head through transverse and longitudinal slits s provided in the under portion of the head H, the said slits being suitably closed as by being stitched after the upper jaw is inserted in the head, the lower jaw member j² being pivotally 35 movable relatively to the upper jaw j' and head H, the said lower jaw being arranged to occupy the position of the lower jaw of the fur piece head.

40 As heretofore mentioned, a principal object of my present invention comprehends the provision of a fur clasp in which the jaw members of the clasp are effectively correlated to perform the clasping function and in which the externally arranged lower jaw member may be made to fully simulate in form, shape and appearance the lower jaw of the animal head, and in which, furthermore, the lower jaw member may be 45 made durable and serviceable with such jaw member retaining its characteristic and neat appearance, irrespective of the period of use or amount of wear to which it is subjected, and in which, moreover, said lower jaw may be 50 constructed in a manner to conceal all metal portions of the clasp. To the accomplishment of these ends the lower jaw j² is fashioned out of a molded material and preferably a composition material such as, 55 for example, a celluloid or bakelite substance or the like, the said jaw j² being given a configuration and contour to effect a full simulation of the lower jaw of the animal and to provide parts for effectively cooperating with the upper jaw j' to eliminate 60

any shearing tendencies during clasping and unclasping and to conceal all metallic portions from view. This is clearly shown in the drawings, and referring more in detail thereto, the lower jaw j² is shaped to 70 provide the front jaw portion 10 and the rear finger grip portion 11 and the intermediate upstanding pintle-bearing ear portions 12 and 13 spaced on opposite sides of the said jaw member. The jaw member when molded is given sufficient "body" and is contoured as clearly shown in the drawings to present the characteristic appearance of the corresponding portion of the animal head, the said jaw member 10 being preferably rounded on its under side and flattened on its top surface and provided at its front end with a pocket or recess 14. In molding the said lower jaw member j² any color may be imparted thereto harmonizing with the type of fur head to which it is to be attached.

75 The upper jaw member j' of my clasp is preferably made of relatively thin sheet material stamped or otherwise shaped to provide the front jaw portion 15 complementary to the lower jaw portion 10 and the rear finger grip portion 16 complementary to the lower grip portion 11, the said upper jaw member j' being further provided with the downturned intermediately located pintle-bearing flange portions 17 and 18 spaced on opposite sides of the said jaw member. For strengthening the jaw member j' the same 80 may be provided with a longitudinal bead or rib 19 and for co-operating with the socket or recess 14 of the lower jaw member the upper jaw member may be provided with a downwardly turned lip 20 adapted to seat within the pocket 14 and effect a firm clasping 85 of the appropriate part of the fur garment.

90 For the purpose of providing a rigid and strong hinge or pivot construction for the jaw members and for the further purpose of correlating the pintle-bearing elements so that the metal portions of the upper jaw member j' are effectively concealed from view, the upstanding ears 12 and 13 of the lower jaw member are grooved longitudinally to provide the recesses or sockets 110 21 and 22 respectively, the said sockets receiving the pintle-bearing flange portions 17 and 18 respectively of the upper jaw member, the construction being such that each ear portion provides upstanding walls on opposite sides of a pintle-bearing flange portion with the pintle-bearing flange portion concealed from view by the exterior ear wall, this being clearly shown, for example, in Figures 3 and 4 of the drawings wherein the ear portion 12 is shown to comprise the outer and inner upstanding walls 12' and 12² arranged on opposite sides of the flange portion 17 and the ear portion 13 is shown to 115 120 125 130

comprise or define the outer and inner wall portions 13' and 13² arranged on opposite sides of the pintle-bearing flange portion 18. The pintle-bearing portions are provided with registering apertures for receiving the hinge pintle or pivot pin 23.

For the purpose of housing or seating the clasp spring, the lower jaw member 7² is suitably channeled in the finger grip portion 11 thereof as at 24, the torsion spring 25 surrounding the pivot pin 13 and having its opposite ends 26 and 27 engaging the finger grip portions 16 and 11 respectively for normally urging the latter for holding the clasp jaws closed being suitably seated in said channel or recess 24, as is clearly shown in Figures 2 to 4 of the drawings.

The manner of constructing my improved fur clasp and attaching the same to the fur piece head will, in the main, be apparent from the above detailed description thereof. It will be further apparent that I have provided a clasp in which the lower movable jaw member is made to simulate in shape, form and appearance the lower jaw member of the animal head, the said clasp when attached to the head of the animal assuming the appearance as shown, for example, in Figures 1 and 2 of the drawings, all metal portions of the clasp being effectively concealed from view with the clasp capable of operation and use without the disadvantages and defects present in prior constructions of this type; the said clasp having no tendency to pull or tear the hair of the fur, the construction of the pintle-bearing members being such as to obviate this tendency, the lower jaw member providing, moreover, a durable and serviceable element retaining its desired appearance, irrespective of use and wear, the clasp as a whole having a neat and attractive appearance.

While I have shown my device in the preferred form, it will be obvious that many changes and modifications may be made in the structure disclosed without departing from the spirit of the invention, defined in the following claims.

I claim:

1. A fur clasp comprising pivoted upper and lower jaw members, the upper jaw member including downwardly turned pintle-bearing flange portions, the lower jaw member comprising a unitary piece provid-

ed with spaced integral upstanding pintle-bearing ear portions, each ear portion being longitudinally grooved to provide a recess or socket receiving a flange portion of the upper jaw, the construction being such that each ear portion provides upstanding walls located on opposite sides of a flange portion with the flange portion substantially concealed by the outer wall and a hinge pintle or pivot pin received by the said pintle-bearing portions.

2. A fur clasp comprising pivoted upper and lower jaw members, the upper jaw member including downwardly turned pintle-bearing flange portions, the lower jaw member comprising a unitary piece provided with spaced integral upstanding pintle-bearing ear portions, the space between the ear portions being recessed to provide a spring receiving pocket, each ear portion being longitudinally grooved to provide a recess or socket receiving a flange portion of the upper jaw, the construction being such that each ear portion provides upstanding walls located on opposite sides of a flange portion, a hinge pintle or pivot pin received by the said pintle-bearing portions and a spring surrounding the pintle and seated in said pocket, the said spring being active for normally urging the jaw members into closing position.

3. A fur clasp comprising pivoted upper and lower jaw members, the upper jaw member including downwardly turned pintle-bearing flange portions, the lower jaw member comprising a unitary piece made of molded composition material molded to simulate in form and appearance the lower jaw of a fur-piece animal head and provided with spaced integral upstanding pintle-bearing ear portions, each ear portion being longitudinally grooved to provide a recess or socket receiving a flange portion of the upper jaw, the construction being such that each ear portion provides upstanding walls located on opposite sides of a flange portion with the flange portion substantially concealed by the outer wall and a hinge pintle or pivot pin received by the said pintle-bearing portions.

Signed at New York city, in the county of New York and State of New York this 10th day of February, A. D. 1922.

SAMUEL GOLDSTEIN.
